UNITED STATES PATENT OFFICE.

LEWIS WASHINGTON BRIGGS, OF NEW YORK, N. Y.

BRUSH-BRIDLE.

SPECIFICATION forming part of Letters Patent No. 634,570, dated October 10, 1899.

Application filed June 8, 1898. Serial No. 682,869. (No model.)

To all whom it may concern:

Be it known that I, LEWIS WASHINGTON BRIGGS, a citizen of the United States, residing at New York, in the county of New York 5 and State of New York, have invented certain new and useful Improvements in Brush-Bridles; and I do hereby declare the following to be a full, clear, and exact description of the invention, such as will enable others skilled in the art to which it appertains to make and use the same.

This invention relates to an improvement in brushes; and its object is to provide a brush with a bridle which serves the double purpose 15 of binder and drip-cup and which may be cut or torn away as the bristles wear.

A further object is to reduce cost and simplify the manufacture of brushes.

To these ends the invention consists in a 20 handle of the usual form, around the shank of which are placed the ends of the bristles. Over the bristles is wrapped a bridle of heavy stiff canvas or other similar fabric, which is doubled over at its inner edge into two or 25 more thicknesses. After drawing the lower reinforced edge of the bridle tight over the bristles it is fastened to the shank by forcing nails, screws, or other suitable objects down through the bristles into the wood. This mode 30 of fastening will serve to separate the bristles into bunches, each of which will be securely bound down to the shank. The shank of the brush projects but a slight distance into the bristles and under the bridle, and thereby 35 leaves the bristles at the outer edge of said bridle loose, although still retained by the stiff bridle. It will be seen that as the bristles wear down the bridle, which is preferably shellacked, may be torn or cut away in strips, 40 as desired.

In the accompanying drawings I have shown the preferred form of my invention.

In said drawings, Figure 1 is a side elevation of a brush embodying my invention. 45 Fig. 2 is a section on line 2 2, Fig. 1. Fig. 3 is a section on line 3 3, Fig. 1; and Fig. 4 is a section similar to Fig. 2, showing the bristles pressed back.

Referring to said figures by letters of reference, A is the handle of the brush, the shank 50 a of which projects a short distance into the

bristles B, which are secured therearound. Said bristles are held in position by means of a bridle C, composed, preferably, of shell-lacked heavy canvas, which projects for a 55 desired distance beyond the end of the shank a. The overlapping ends of said bridle are free, so as to permit the insertion of scissors or other implements for the purpose of decreasing the length of said bridle by cutting 60 or tearing.

The lower edge of the bridle C is folded over one or more times, as at D, so as to stiffen and strengthen the same. This edge is drawn tightly around the ends of the bristles and is 65 secured to the shank a by means of nails, screws, or other suitable objects E, which pass through said bristles and serve to separate the same into bunches, thereby holding them compactly and securely together. 70

Although the two edges of the bridle are of the same length, the bristles are loosely held at the outer edge for the reason that the shank a projects but a slight distance into the bridle, and thus leaves additional space 75 for the play of the bristles within said outer edge.

As bridle C is of stiffened fabric when the bristles B are compressed on the backward and forward sweeps of the brush a space is 80 formed along the edge of the bridle, which serves to receive all superfluous color and prevent its trickling down to the handle. The loose bristles are also enabled to absorb more color and the same can be applied evenly. 85

As the bristles wear down the bridle may be reduced in length by tearing or cutting, and the life of the brush is thereby greatly prolonged.

In the foregoing description I have shown 90 the preferred form of my invention; but I do not limit myself thereto, as I am aware that modifications may be made therein without departing from the spirit or sacrificing the advantages thereof, and I therefore reserve 95 the right to make such changes as fairly fall within the scope of my invention.

The inner ends of the bristles B are preferably coated over with paint or other suitable material, which serves to protect the 100 bristles from moisture, &c., as well as to give a finished appearance to the brush.

Having thus described my invention, what I therefore claim as new, and desire to secure by Letters Patent thereon, is—

1. As a new article of manufacture, the paint or color brush consisting of the bristles, the handle, and the bridle and binder in one piece formed of suitable yielding but non-elastic material, said handle having its inner end stopping within the outer end or edge of said bridle, and said bridle having its outer end or edge free or adapted to permit the bristles to yield or flex within the bridle to form a drip-cup, substantially as shown and described.
- 15 2. As a new article of manufacture, the paint or color brush consisting of the bristles, the handle and the bridle of suitable stiffened material, said handle having its inner end stopping intermediately of the inner and outer ends or edges of said bridle, and said bridle having its outer ends or edges free or adapted to permit the bristles to yield or flex within the bridle, substantially as set forth.
- 20 3. As a new article of manufacture, the paint or color brush consisting of the bristles, the

handle and the bridle of stiffened, flexible material, said handle having its inner end terminating intermediately of the ends or edges of said bridle and said bridle having its outer end or edge adapted to permit the bristles to yield or flex within the bridle, and its inner end or edge adapted to bind the inner ends of said bristles, substantially as set forth. 30

4. As a new article of manufacture, the paint or color brush, consisting of the bristles, the bridle and the handle, said handle having its inner end terminating a short distance inward from the outer end or edge of said bridle, and said bridle adapted to permit said bristles to yield or flex within the bridle, and 35 having its inner end reinforced and a row of closely-arranged nails or fastenings driven therethrough and through said bristles and into said handle, substantially as set forth.

In testimony whereof I affix my signature 40
in presence of two witnesses.

LEWIS WASHINGTON BRIGGS.
